(57) **CLAIM**

The ornamental design for automobile tire tread, as shown and described.

DESCRIPTION

FIG. 1 is a front view of an automobile tire tread, showing the new design, a top plan view thereof, a bottom plan view and a rear view thereof appearing the same as the front view; FIG. 2 is a right side view of the automobile tire tread, a left side view appearing the same as the right side view; FIG. 3 is a fragmentary front view, showing in enlargement the portion of lines III—III in FIG. 1; and, FIG. 4 is a cross-sectional view taken along line IV—IV and in the direction of arrows in FIG. 3. The broken line showing of a tire sidewall and inner bead, and the peripheral boundary between the tire tread and sidewall, indicate unclaimed environment and form no part of the claimed design.
